FASTENING FOR RAILWAY RAILS

Jacob Rush Snyder, Cleveland, Ohio

Application September 3, 1948, Serial No. 47,654

7 Claims. (Cl. 238—349)

1

This invention relates to fastenings for railway rails and, more particularly, to rail fastenings of the kind which includes a spike driven into a wood tie and a substantially rigid clamp which is subjected to spring pressure for yieldingly holding the rail against a tie plate.

An object of the present invention is to provide an improved rail fastening of this kind in which the spike has increased holding power in the tie by reason of the fact that the portion of the tie surrounding a preformed bore into which the spike is driven is chemically treated and hardened and thereby rendered resistant to shearing, crushing, fraying or rotting and also by reason of the fact that the treating material establishes an adhesive bond between the spike and wood tie.

Another object of this invention is to provide such an improved rail fastening which includes yieldable holding means engaging a rail flange, or a rail flange and a tie plate, and in which the spike of the fastening has the above-mentioned increased holding power in the treated spike hole of the tie.

Another object is to provide an improved rail fastening of the character mentioned in which the spike is a so-called cut spike having a plain stem as distinguished from a screw spike having a threaded stem.

Still another object is to provide an improved rail fastening of the character referred to in which a coil spring surrounding the spike serves the dual purpose of applying a desired load to the rigid clamp and acting as a gauge or stop for limiting the extent to which the spike is driven into the tie.

A further object of this invention is to provide an improved rail fastening of the character mentioned in which the treating chemical is pressurized into the wood during the driving of the spike and the rigid clamp has an inclined spring seat thereon adapted to cooperate with the spring so as to enable the spring to act as a gauge for the spike without preventing a desired yielding and rocking of the clamp to permit a limited amount of movement of the rail relative to the tie plate.

Yet another object of the invention is to provide an improved rail fastening of the character mentioned above and in which the chemical material is a water-insolvent cold-setting glue, preferably a potentially thermo-setting resin material such as a synthetic resin of the aldehyde type or a mixture of an aldehyde resin and a vinyl resin and which resin material is rendered actually thermo-setting by the addition of a

2

catalytic material or hardener thereto such as formaldehyde.

Other objects and advantages of the invention will be apparent in the drawing and in the following detailed description.

This application is related to copending applications Serial No. 29,132, filed May 25, 1948, and Serial No. 47,653, filed September 3, 1948, in which metal-to-wood fastenings embodying a wood-hardening glue are disclosed and claimed.

In the accompanying sheets of drawings,

Fig. 1 is a partial plan view showing a rail fastening embodying the present invention;

Fig. 2 is a vertical transverse section taken through the rail and tie plate at a point adjacent the clamp, as indicated by section line 2—2 of Fig. 1, and showing the clamp in side elevation;

Fig. 3 is a vertical section taken through the fastening in a direction transversely of the rail, as indicated by section line 3—3 of Fig. 1;

Fig. 4 is a sectional plan view taken through the fastening substantially on the irregular section line 4—4 of Fig. 3;

Fig. 5 is a perspective view of the rigid clamp in detached relation;

Fig. 6 is a transverse sectional detail taken on line 6—6 of Fig. 3;

Fig. 7 is a partial plan view similar to Fig. 1 but showing a modified form of the improved rail fastening;

Fig. 8 is a partial vertical section taken through the modified fastening in a direction transversely of the rail, as indicated by section line 8—8 of Fig. 7; and

Fig. 9 is a perspective view showing the rigid clamp of the modified fastening in detached relation.

In the form of the improved rail fastening illustrated in Figs. 1 to 5, inclusive, the drawings show a wood tie 10 having a tie plate 11 supported thereon. A conventional railway rail 12 has its base flange 13 resting on the tie plate. The improved fastening also includes a fastening member in the form of a spike 14 driven into the tie and a substantially rigid clamp 15 against which a coil spring 16 is compressed and which clamp applies pressure to the tie plate 11 and the rail flange 13.

The tie 10 is a wood member such as a conventional tie which has been sawed or otherwise prepared from oak, pine or other suitable kind of wood timber. The tie may have its outer surface creosoted, as is conventional practice in present day railroad construction. The tie 10 is provided with a preformed bore 17 which extends

tion transversely of the grain of the wood. For a reason to be further explained hereinafter and as shown in Fig. 6, the diameter of the bore 17 is smaller than the minimum transverse dimension of the stem of the spike 14. For example, when the spike has a $\frac{5}{8}$ inch square stem the bore would be $\frac{1}{2}$ inch or $\frac{9}{16}$ inch in diameter.

The tie plate 11 is a conventional metal tie plate having an opening 18 therein for the stem of the spike 14 and which plate is supported on the tie 10 with the opening in overlying relation to the preformed bore 17. The tie plate 11 is provided with an upstanding shoulder 19 extending thereacross and adapted to be engaged by an edge of the base flange 13 for gauging or positioning the rail. The opening 18 extends through the tie plate at a point adjacent the base flange 13 and, in this instance, extends through the rail-gauging shoulder 19. The tie plate 11 may also be provided with one or more other openings 20 which extend therethrough at a point spaced outwardly from the shoulder 19.

The clamp 15 is a substantially rigid L-shaped one-piece metal member extending in arched relation over the rail-gauging shoulder 19 of the tie plate 11. The clamp is disposed so that the stem of the L-shape forms an arm 21 which extends inwardly toward the rail 12 in overhanging relation to the base flange 13. The arm 21 is provided at its inner end with an end bearing portion 22 which engages the top of the base flange 13. The base of the L-shape is disposed in upright relation and forms the outer end 23 of the clamp. The upright outer end 23 is provided at its lower edge with a transverse seat or shoulder 24 which rests on the tie plate at a point just outwardly of the opening 18. At an intermediate point thereof the clamp 15 is provided with an opening 25 through which the spike 14 extends and which overlies the opening 18 of the tie plate. The clamp is provided with a substantially flat top bearing surface 26 which surrounds the opening 25 and forms a seat for the lower end of the spring 16.

The spike 14 is here shown as being a cut spike having a head 14a and a stem 14b which is driven into the bore 17 of the tie through the opening 18 of the tie plate and the opening 25 of the clamp. The stem 14b is a plain or unthreaded stem, as distinguished from the threaded stem of a screw spike, and is preferably of a substantially square cross-sectional shape. As is common in railway spikes of this character, the inner end of the stem is provided with a substantially chisel-shaped point 14c. The head 14a has a flat surface on the underside thereof forming a seat 27 for the upper end of the spring 16. At the junction of the head 14a with the square stem 14b the spike is preferably provided with an enlargement or shoulder 28 of a substantially circular cross-section which telescopes into the upper end of the spring 16.

The spring 16 is a coil spring of suitable characteristics which is disposed around the stem of the spike 14 and is compressed against the bearing surface 26 of the clamp 15 by the head of the spike. The spring applies pressure to the clamp which, in turn, transmits the pressure to the tie plate 11 and the flange 13 of the rail 12. The pressure applied to the tie plate by the outer end bearing portion 24 of the clamp holds the tie plate firmly against the tie 10. The pressure applied to the rail flange 13 by the inner end bearing portion 22 of the clamp yieldingly holds the rail against the tie plate. During the pas-

sage of trains over the track the rail 12 is subject to some lifting or springing away from the tie plate 11 which is permitted by a rocking of the clamp on its outer end bearing portion 24 as a fulcrum. During this rocking of the clamp the arm portion 21 rises and falls relative to the tie plate as permitted by the flexing of the spring 16.

Reverting to the top bearing surface 26 of the clamp 15, it is pointed out that this surface is inclined relative to the axis of the spike 14 and slopes downwardly and inwardly toward the rail flange 13. As shown in the drawings, the upright outer end portion 23 of the clamp forms the high side of the inclined bearing surface and the arm portion 21 of the clamp forms the low side of the inclined bearing surface. In addition to the function of applying pressure to the clamp 15, the spring 16 also serves as a gauge or stop for limiting the extent to which the spike 14 is driven into the tie 10 and the ability of the spring to do this is made possible by the inclination of the bearing surface 26 of the clamp.

In assembling the improved fastening the spike 14 is driven into the bore 17 of the tie 10 for a distance to cause the convolutions at the outer side of the spring 16, that is the side remote from the rail 12, to be compressed to a substantially solid condition. Because of the inclined relation of the bearing surface 26 the convolutions at the opposite or the inner side of the spring will remain spaced apart, as shown in the drawings. When the convolutions at the outer side of the spring have been thus compressed to a substantially solid condition this portion of the spring will act as a stop for preventing the spike from being driven further into the tie and the extent to which the spring has been compressed or loaded will then be such as to apply the desired pressure to the clamp 15. The compression of the convolutions to a substantially solid state at the outer side of the spring during the installation of the fastening is usually only a temporary condition because as soon as a few trains have passed over the track the tie plate will settle somewhat into the tie and the looseness thus produced will be taken up by the spring and will result in a desired slight separation between the convolutions at the outer side of the spring.

In the improved fastening as above described, the enlargement or shoulder 28 of the spike 14 extends into the upper end of the spring 16 and serves as a holding and positioning means which tends to maintain the spring with its convolutions in vertical alignment and also acts through the spring in maintaining the clamp 15 in proper position. The inner end of the clamp 15 is preferably provided with an upstanding transverse flange or shoulder 30 which is engaged by the outside of the lower end of the spring 16 so that shifting of the clamp in a direction away from the rail will be resisted by the spring. The opening 25 of clamp 15 is preferably rectangular so as to cooperate with the square stem of the spike in preventing rotation of the clamp about the spike and the opening is of such size that its sides will engage the spike and limit the lateral shifting of the clamp in a direction longitudinally of the rail. The engagement of the spring with the shoulder 30 enables the spring to hold the clamp in such position that the inner end of the clamp opening 25 will not scrape against the spike during the above-explained rocking of the clamp on the end portion 24. In the arrangement just

5

described the rectangular opening of the clamp and the square opening 18 of the tie plate enable the square stem 14b of the spike 14 to hold the clamp in proper position and prevent turning thereof.

The head 14a of the spike 14 is preferably of a size such that the underside 27 thereof will project laterally beyond the spring 16 and will present a flat surface or shoulder adapted to be engaged by a spike pulling machine when it is desirable to use a power device of this kind for pulling the spike out of the tie. To permit the use of a hand operated spike pulling tool of the claw type, the outer end bearing portion 24 of the clamp 15 is provided with notches or recesses 31 at opposite sides thereof which permit the claws of the tool to engage under the outer end of the clamp.

In the form of the invention illustrated in Figs. 7 to 9, inclusive, a rail fastening is shown which is similar to the fastening illustrated in Figs. 1 to 5, inclusive, but in which the tie plate 11 is provided with an opening 32 having an extension recess or keyway 33 formed in the side thereof remote from the rail 12 and the clamp 34 is provided with a depending lug or key 35 as an integral extension of the outer end bearing portion 24 and which lug engages in such extension recess or keyway. Since the depending lug 35, when engaged in the recess 33, will effectively prevent outward shifting of the clamp 34, the upstanding transverse flange 30 has been omitted. In other respects the fastening of Figs. 7 to 9, inclusive is the same as the fastening illustrated in Figs. 1 to 5, inclusive, and described above and the same reference characters have been applied to corresponding parts.

In accordance with an important feature of the present invention, the spike 14 has increased holding power in the wood tie 10 and as the result of which a rail fastening of the type embodying a substantially rigid clamp and a coil spring for applying pressure thereto becomes much more practical and satisfactory for use on railway track. This increased holding power also makes possible the above described use of so-called cut spikes having a plain or unthreaded stem in place of the more expensive screw spikes or hook bolts which have been required heretofore. In obtaining this increased holding power for the spike the portion of the wood tie 10 immediately surrounding the bore 16 is treated with a chemical material indicated at 36 in the drawings and is thereby hardened and reinforced and rendered resistant to crushing, fraying, shearing and rotting. The material 36 also establishes an adhesive bond between the stem of the metal spike 14 and the wood of the tie.

The chemical material used in treating the portion of the tie surrounding the bore 16 can be any material suitable for this purpose which will produce the results explained above. This chemical material is preferably a cold-setting water-insoluble glue which is initially plastic or fluid in character and can be readily introduced into the bore 16 and trapped therein for pressurization into the wood during the driving of the spike 14. As this treating material any one of various synthetic resins can be used, for example a resin of the aldehyde or phenol aldehyde class such as phenol formaldehyde, urea formaldehyde, melamine formaldehyde or resorcinol formaldehyde.

The treating materials just mentioned are potentially thermo-setting in character and are

6

rendered actually thermo-setting by the mixing of a hardener or so-called catalyst therewith, such as formaldehyde, and the mixture formed by the resin and the hardener constitutes the treating material which is indicated at 36 in the above described rail fastenings. The hardener can be in either a powdered or liquid form and is added to the resin in suitable amounts, such as 5 per cent to 50 per cent by weight of the hardener to 95 per cent to 50 per cent by weight of the resin, but the amount of the hardener to be used can be varied and will depend upon various factors including the specific resin employed and the setting characteristics desired for the treating material. Ordinarily, an amount of the hardener is employed which will produce setting of the resin in a period of from one to four hours at a normal temperature, that is to say, a temperature ranging from 65 degrees to 90 degrees Fahrenheit.

It is important that the treating material 36 establish an adhesive bond between the wood tie and the spike as mentioned above. It is also important to prevent the treating material 36 from assuming a brittle state in which cracking or crazing might occur in such material when it has become set. Both of these characteristics are obtained for the treating material 36 by incorporating a plasticizing agent, such as a suitable thermo-plastic material, in the aldehyde resin prior to the mixing of the catalyst or hardener therewith. As this plasticizing agent a vinyl resin can be used such as vinyl acetate or vinyl butyral. The preferred plasticizing agent can be designated as a partially hydrolyzed polyvinyl acetate. The amount of the plasticizer to be used can be varied depending upon the particular aldehyde resin employed and the setting characteristics desired for the material. When the above mentioned polyvinyl acetate is used as the plasticizer 2 per cent to 20 per cent by weight is added to the resin. The treating material or glue 36 then comprises by weight approximately 93 per cent to 30 per cent of the aldehyde resin. Approximately 2 per cent to 20 per cent of the vinyl resin and approximately 5 per cent to 50 per cent of formaldehyde as a hardener.

It has been established by tests that when conventional cut spikes of the type commonly used in railroad track construction, such as a cut spike having a $\frac{5}{8}$ inch square by $5\frac{1}{2}$ inch long stem, are driven into creosoted new wood ties, such as red oak ties having preformed $\frac{1}{8}$ inch diameter by 6 inch long bores therein for the spikes, an average force of approximately 3,000 pounds will be required to pull the individual spikes out of the ties. As illustrative of the increased holding power of the spike 14 in the tie 10 by reason of the use of the treating material 36 with which the portion of the tie surrounding the bore 16 is impregnated, it is explained that when such a treating material was used in actual tests and consisted of approximately 95 per cent to 50 per cent by weight of resorcinol formaldehyde resin and approximately 5 per cent to 50 per cent by weight of formaldehyde as a catalyst or hardener and was pressurized into the wood during the driving of the spikes and had become set, an average force of 5,000 pounds was required to pull the spikes out of the ties. When the treating material comprised approximately 84 per cent by weight of resorcinol formaldehyde resin, approximately 4 per cent by weight of vinyl resin and approximately 12 per cent by weight of formaldehyde as

a catalyst or hardener, an average force of 5,000 pounds to 6,000 pounds was needed to pull the spikes out of the ties. When the treating material comprised approximately 75 per cent by weight of resorcinol formaldehyde resin, approximately 14 per cent by weight of vinyl resin and approximately 11 per cent by weight of formaldehyde as a catalyst or hardener, an average force of from 7,500 pounds to 9,000 pounds was needed to pull the spikes out of the ties.

It should be explained further that when the portion of the tie surrounding the bore has been reinforced by chemical treatment, as explained above, and the treating material has become set the wood will be materially hardened and greatly strengthened and will also be rendered substantially non-absorbent and highly resistant to rotting.

The increased hardness of the portion of the tie surrounding the spike 14 will cause the spike 20 to be firmly held against lateral shifting during a prolonged period of service and loosening of the spike in the tie will thus be effectively prevented. In addition to this ability of the reinforced tie portion to firmly hold the spike against lateral shifting and to resist crushing, shearing and rotting of the wood fibers, the adhesive bond established by the treating material between the spike and the wood particularly when the vinyl resin is incorporated in the material results in the spike being also strongly held against axial movement out of the tie. It should also be explained that in forming this improved rail fastening the treating material or glue is preferably placed in the bore 16 in a bulk state although it can, if desired, be contained in a frangible capsule, and is forced into the surrounding portion of the wood tie during the driving of the spike. When the spike is initially started into the bore 16 some of the treating material 36 will flow upwardly around the spike, as indicated at 37, and will form a protective coating and seal at this point which will prevent brine, or the like, dripping from railway cars from corroding the spike at this point.

From the foregoing description and the accompanying drawings it will now be readily understood that this invention provides an improved rail fastening, of the type embodying a substantially rigid clamp subjected to spring pressure, and which is simple in construction and very durable and reliable in service and requires the use of only relatively few parts adapted to be economically manufactured and installed. It will now also be understood that the increased holding power and durability, derived from the use of the chemical material with which the tie portion surrounding the bore is impregnated, permits the use of a cut spike having a plain or unthreaded stem in place of the more expensive screw spike or hook bolt which has heretofore been required in rail fastenings of this type. Additionally, it will be seen that the improved fastening provided by this invention will contribute greatly to the longer life of the wood tie because the tie plate will always be firmly held against the tie and pounding of the tie plate which has heretofore resulted in cutting and fraying of the tie will be substantially prevented.

Although the improved rail fastening provided by this invention has been illustrated and described herein to a detailed extent it will be understood, of course, that the invention is not to be regarded as being limited correspondingly in

scope but includes all changes and modifications coming within the terms of the claims hereof.

Having thus described my invention, I claim:

1. In a rail fastening, a wood tie having a preformed bore therein, a tie plate on said tie and having an opening overlying said bore, a rail having a base flange resting on said tie plate, a clamp comprising a substantially rigid one-piece metal body having one portion bearing on said tie plate and another portion engaging the top of said base flange, said clamp also having an opening therein between said portions and a spring seat surrounding said opening, a spike having a plain stem driven into said bore through the openings of said tie plate and clamp and a head spaced above said spring seat, said stem having a tight-fitting engagement in said bore such that portions of said stem are in direct contact with the portion of said tie immediately surrounding said bore, a coil spring disposed around said stem and compressed against said seat by said head, and a quantity of initially fluid but settable synthetic resin glue in said bore and distributed through the wood of such surrounding portion of said tie and which in its set condition hardens the wood of said surrounding portion for increased holding engagement of said stem therewith and also forms an adhesive bond directly between said stem and tie internally of the latter.

2. In a rail fastening of the character described, a wood tie having a preformed bore therein, a tie plate on said tie and having an opening overlying said bore, a rail having a base flange resting on said tie plate, a substantially rigid clamp having one portion bearing on said tie plate and another portion engaging the top of said base flange, said clamp also having an opening therein between said portions and a spring seat surrounding said opening, a spike having a stem driven into said bore through the openings of said clamp and tie plate and also having a head spaced above said spring seat, said stem having a tight-fitting engagement in said bore such that portions of said stem are in direct contact with the wood of the side wall of said bore, and a coil spring surrounding said stem and compressed against said spring seat by said head, the portion of said tie immediately surrounding said bore being impregnated with an initially fluid water-insoluble cold-setting synthetic resin glue which in its set condition imparts increased hardness and durability to such tie portion and said stem having increased holding power in said impregnated tie portion by reason of said increased hardness of said tie portion.

3. In a rail fastening of the character described, a wood tie having a preformed bore therein, a tie plate on said tie and having an opening overlying said bore, a rail having a base flange resting on said tie plate, a substantially rigid clamp having one portion bearing on said tie plate and another portion engaging the top of said base flange, said clamp also having an opening therein between said portions and a spring seat surrounding said opening, a spike having a stem driven into said bore through the openings of said clamp and tie plate and also having a head spaced above said spring seat, said stem having a tight-fitting engagement in said bore such that portions of said stem are in direct contact with the wood of the side wall of said bore, and a coil spring surrounding said stem and compressed against said spring seat by

said head, the portion of said tie immediately surrounding said bore being impregnated with an initially fluid thermo-setting resin which in its set condition imparts increased hardness and durability to such tie portion and said stem having increased holding power in said tie by reason of the increased hardness of said tie portion, said thermo-setting resin also forming an adhesive bond directly between said stem and said tie internally of the latter.

4. In a rail fastening of the character described, a wood tie having a preformed bore therein, a tie plate on said tie and having an opening overlying said bore, a rail having a base flange resting on said tie plate, a substantially rigid clamp having one portion bearing on said tie plate and another portion engaging the top of said base flange, said clamp also having an opening therein between said portions and a spring seat surrounding said opening, a spike having a stem driven into said bore through the openings of said clamp and tie plate and also having a head spaced above said spring seat, said stem having a tight-fitting engagement in said bore such that portions of said stem are in direct contact with the wood of the side wall of said bore, and a coil spring surrounding said stem and compressed against said spring seat by said head, the portion of said tie surrounding said bore being impregnated with a thermo-setting resin which in its set condition imparts increased hardness and durability to such tie portion and said plain stem having increased holding power in said tie by reason of the increased hardness of said tie portion, said resin being initially contained in said bore in a fluid condition and the bore being of a smaller diameter than the minimum transverse dimension of said stem such that during the driving of said spike said resin will be trapped and pressurized thereby in said bore and forced into said surrounding tie portion, said resin in its set condition also forming an adhesive bond directly between said stem and said tie internally of the latter.

5. In a rail fastening of the character described, a wood tie having a preformed bore therein, a tie plate on said tie and having an opening overlying said bore, a rail having a base flange resting on said tie plate, a substantially rigid clamp having one portion bearing on said tie plate and another portion engaging the top of said base flange, said clamp also having an opening therein between said portions and a spring seat surrounding said opening, a spike having a stem driven into said bore through the openings of said clamp and tie plate and also having a head spaced above said spring seat, said stem having a tight-fitting engagement in said bore such that portions of said stem are in direct contact with the wood of the side wall of said bore, and a coil spring surrounding said stem and compressed against said spring seat by said head, the portion of said tie surrounding said bore being impregnated with an initially fluid but settable thermo-setting resin which in its set condition imparts increased hardness and durability to such tie portion and said stem having increased holding power in said impreg-

nated tie portion, said thermo-setting resin comprising a mixture of synthetic resin of the aldehyde class and a vinyl resin and said mixture being rendered thermo-setting by the addition of formaldehyde thereto as a hardener.

5 6. In a rail fastening, a wood tie having a preformed bore therein, a rail supported by said tie and having a base flange, holding means of the yieldable type engaging said base flange for 10 yieldably holding said rail relative to said tie including a fastener having a stem driven into said bore, said stem having a tight-fitting engagement in said bore such that portions of said stem are in direct contact with the wood of the side wall of said bore, the portion of said tie surrounding said bore being impregnated with an initially fluid but settable wood-hardening and preservative material which in its set condition hardens the impregnated portion of said tie and forms an adhesive bond between said stem and tie such that said fastener has increased holding power in said impregnated tie portion.

15 7. In a rail fastening, a wood tie having a preformed bore therein, a tie plate on said tie and having an opening overlying said bore, a rail having a base flange resting on said tie plate, holding means of the yieldable type having one portion engaging said base flange for yieldably holding said rail relative to said tie plate and another portion engaging said tie plate for 20 yieldably holding said tie plate relative to said tie and said holding means including a spike having a plain stem driven into said bore through said opening of the tie plate, said stem having a tight-fitting engagement in said bore such that portions of said stem are in direct 25 contact with the portion of said tie immediately surrounding said bore, such surrounding portion of the tie being impregnated with an initially fluid but settable water-insoluble cold-setting synthetic resin glue which in its set condition hardens the wood of said surrounding portion and also forms an adhesive bond between said stem and wood tie.
